Primary Examiner — Cynthia R Underwood*(74) Attorney, Agent, or Firm* — Barnes & Thornburg LLP(57) **CLAIM**

The ornamental design for a vent hood, as shown and described.

DESCRIPTION

FIG. 1 is an Upper Perspective View of the invention.
 FIG. 2 is a Lower Perspective View of the invention.
 FIG. 3 is a Top Planar View of the invention.
 FIG. 4 is a Bottom Planar View of the invention.
 FIG. 5 is a Front Planar View of the invention.
 FIG. 6 is a Back Planar View of the invention.
 FIG. 7 is a Left Side Planar View of the invention; and,
 FIG. 8 is a Right Side Planar View of the invention.
 Portions shown in broken lines are for environmental purposes but do not constitute a part of the claimed invention.
